Farnum F. Dorsey

UNITED STATES PATENT OFFICE.

ALBERT F. STAPLES, OF DORCHESTER, MASSACHUSETTS.

ASH-SIFTER.

1,279,605.

Specification of Letters Patent. Patented Sept. 24, 1918.

Application filed March 2, 1918. Serial No. 220,071.

To all whom it may concern:

Be it known that I, ALBERT F. STAPLES, a citizen of the United States, residing at Dorchester, in the county of Middlesex and 5 Commonwealth of Massachusetts, have invented certain new and useful Improvements in Ash-Sifters; and I do hereby declare the following to be a full, clear, and exact description of the invention, such as will enable 10 others skilled in the art to which it appertains to make and use the same.

This invention relates to ash-sifters of the type in which a shovel-like body, of wire-netting or other foraminous material is used 15 in the manner of a shovel, to scoop up the ashes in the ash-pit of a furnace or stove, and also as a sifter to separate the cinders from the ashes.

In sifters of the type in question, as shown 20 for example in United States Letters Patent No. 1,241,677, granted to the present applicant October 2nd, 1917, it is common to employ, at the forward end of the body of the sifter, a sheet-metal member which is hinged 25 or pivoted to the body in such a manner that it may be swung alternatively into upright position, to serve as an end-closure for the body, or into horizontal position to act as a lip. In the latter position the pivoted member 30 is introduced into or beneath the body of ashes which is to be raised and sifted, and it is necessary that when so used it shall be retained firmly in proper relative position to the body, so as not to be accidentally 35 swung up and closed in the act of filling the sifter with ashes.

An object of the present invention is to provide simple but effective means for locking the end-closure in open position, these 40 means being associated with the manually operable means by which the end-closure is moved from one position to the other, so that a single continuous movement of the manually operable means is sufficient both to move 45 the end-closure and to lock or unlock it, as the case may be.

Another object of the invention is to provide effective means for stiffening and reinforcing the foraminous body and for supporting the said locking means in operative position.

A third object is to provide the sifter with means for confining the dust produced in the operation of sifting.

55 To the foregoing ends the invention consists in the construction hereinafter de-

scribed, as it is defined in the annexed claims.

In the accompanying drawings Figure 1 is a plan-view of a sifter embodying the 60 present invention, with a portion of the handle broken away. Fig. 2 is a section on the line 2—2 in Fig. 1; and Fig. 3 is a side-elevation of the sifter, showing the end-closure in closed position. Fig. 4 is a cross-sectional view on line 4—4 of Fig. 2.

The invention is illustrated as embodied in a sifter in which the body 5 is formed of wire-netting, which is clasped, at its upper edge, by a doubled strip 6 of sheet-metal, 70 and secured by rivets. The body is reinforced at the bottom by a metal strip 7, which is secured to the forward end of the handle 8 of the sifter. The pivoted end-closure 9 is formed of sheet-metal and is secured, by a hinge-joint 10, to a sheet-metal member 11 fixed at the forward edge of the wire-netting. The body is braced, and further secured to the handle, by an inclined strip 12 of metal which is fixed, at its rear 75 end, to the top of the handle, and at its forward end to the member 11. The brace 12 and the strip 7, attached to the upper and lower surfaces of the handle, produce a truss-like structure by which the flexible 80 wire-netting is rigidly attached to and supported from the handle.

For the purpose of moving and locking the end-closure 9 a toggle-mechanism is employed, comprising a short link 13 which is pivoted, at 14, to the brace 12. The free end of the link 13 is pivotally attached to a rod or link 15, of which the forward end is pivoted in a lug 16 struck up from the end-closure. A second rod 17 is pivoted to the free end of the link 13 and extends backwardly along the handle 8, terminating in a loop 18. This loop is placed within convenient distance of the cross-grip 19 of the handle, so that both the loop and the grip 95 may be grasped simultaneously by one hand when the end-closure is in closed position, as shown in Fig. 3. In this position of the parts the end-closure is retained in the desired operative position through the agency 100 of the rod 17 and the toggle-mechanism.

The end-closure is provided with runners 20 at its ends, by which the forward end of the body may be supported when it is closed and in use as a sifter, as shown 110 in Fig. 3. When the end-closure is to be opened to the position of Figs. 1 and 2, this

may be readily accomplished either by pressure of the runners against the floor, with the handle held in upright position, or by pressing against the toggle-mechanism 5 through the rod 17. When the end-closure has been fully opened a further pressure through the rod 17 moves the toggle-mechanism slightly below straight-line position, as shown in Fig. 2, so that any tendency of 10 the end-closure to swing upwardly is positively resisted, and thus the end-closure is securely locked in position to act as a lip. When the user desires to move the end-closure to closed position it is necessary 15 merely to pull upon the rod 17, which then acts first to draw the toggle-mechanism upwardly so as to unlock the end-closure, and then to swing the link 13 rearwardly, thus pulling upon the rod 15 and drawing the 20 end-closure to closed position.

The sifter is designed particularly for sifting ashes in the ash-pit of a furnace or heater. When so used the dust produced by the sifting operation is carried away by 25 the draft of the furnace. In order to insure this action, and to confine the dust to the degree necessary to prevent it from being accidentally discharged through the door of the ash-pit, the sifter is provided with 30 a skirt-like guard 21 which incloses the body 5 at the sides and the rear. This guard is conveniently made integral, as shown, with the member 6, and it depends therefrom at a sufficient distance from the body 5 to permit 35 the ashes to fall between the body and the guard. When the contents of the sifter are thrown against the rear end of the body 5, in the operation of sifting, the guard prevents the ashes and dust from being projected 40 from the body with sufficient force to be thrown out of the ash-pit, as might occur in the absence of such guard.

The invention is not limited to the embodiment thereof hereinbefore described 45 and illustrated in the accompanying drawings, but it may be embodied in various other forms within the scope of the following claims.

The invention claimed is:

50 1. In an ash-sifter, the combination, with a foraminous body and a member pivoted to the forward end of the body and movable into position to constitute, alternatively, an end-closure and a lip for the body, of a locking-device for locking the end-closure in 55 open position; and a manually operable member connected with the end-closure and

the locking-device and operable, by a single continuous movement, first to unlock the end-closure and then to move it into closed 60 position.

2. In an ash-sifter, the combination, with a handle, a foraminous body and a member pivoted to the forward end of the body and movable into position to constitute, alternatively, an end-closure and a lip for the body, of a toggle-lever for moving the end-closure and for locking it in open position; and a manually operable rod connected with the toggle-lever and extending along the 70 handle to a position convenient for use.

3. In an ash-sifter, the combination, with a foraminous body comprising a forward horizontal portion and an upright rear portion, and a handle attached to the upper 75 part of said rear portion, of an inclined brace extending directly, from the handle, forwardly within the body to a point on said forward horizontal portion.

4. In an ash-sifter, the combination, with 80 a handle and a foraminous body, of a brace extending, from the lower end of the handle, forwardly within the body to a point of attachment at the bottom of the body; a member pivoted to the forward end of the 85 body and movable into position to constitute, alternatively, an end-closure and a lip for the body; and means, for controlling said member, mounted on said brace.

5. In an ash-sifter, the combination, with 90 a handle, a foraminous body, and a member pivoted to the forward end of the body and movable into position to constitute, alternatively, an end-closure and a lip for the body, of a brace extending, from the handle, forwardly within the body to a point of attachment to the bottom of the body; a toggle-link pivoted to said brace; a link connecting said toggle-link with the end-closure; and a rod pivoted to said link and 95 extending, along the handle, to a point convenient for manipulation.

6. In an ash-sifter, the combination, with a handle and a foraminous body, of a skirt-like guard depending outside of said body 100 and spaced therefrom.

7. In an ash-sifter, the combination of a foraminous body; a support, for the upper edge of the body, formed of doubled sheet-metal embracing said edge; and a guard, at the outside of the body, comprising an integral downward extension of the outer fold of sheet metal.

ALBERT F. STAPLES.
